UNITED STATES PATENT OFFICE.

PETER KAUFMAN AND BENJAMIN KAUFMAN, OF BLOOMINGTON, ILLINOIS.

CORN-HUSKING IMPLEMENT.

SPECIFICATION forming part of Letters Patent No. 237,877, dated February 15, 1881.

Application filed November 3, 1880. (Model.)

To all whom it may concern:

Be it known that we, PETER KAUFMAN and BENJAMIN KAUFMAN, both of Bloomington, in the county of McLean, and in the State of Illinois, have jointly invented certain new and useful Improvements in Corn-Husking Implements; and we do hereby declare that the following is a full, clear, and exact description thereof, reference being had to the accompanying drawings, and to the letters of reference marked thereon, making a part of this specification, and in which—

Figure 1 represents our improved implement and the shield as applied to the hand of a person; Figs. 2 and 3, detached side and front views of the implement; Fig. 4, detached view of the shield.

This invention relates to certain new and useful improvements in corn-husking implements, having for its object the production of an implement that is especially adapted to be held in the hand in the easiest and firmest position, with the husking-point extending over the forefinger of the hand, where the thumb clasps or presses against it, so as to make the operation of husking natural and easy to the hand; and to this end the invention consists in a novel construction of corn-husking implement, as will be hereinafter fully described, and specifically pointed out in the claim.

In the drawings, A represents our improved husking implement, formed from a single piece of wire or other suitable material bent to form a loop, B, with a projecting angular portion, a, that forms the husking-point, which is curved or bent at b to conform to the shape of the thumb. The loop B is made large enough to pass over all the fingers of the hand, and be grasped by said fingers between the second and knuckle joints thereof, with the portion a projecting over the forefinger, so that said portion will be clasped between the forefinger and thumb. The end c of the wire is beveled off and rests upon the main portion thereof, so as to form a spring-clasp, by which the implement can be secured to a leather shield, C, passing around the hand inside of the loop B.

The ends of said shield overlap, and one end is provided with an opening, d, and the other end cut to form a strip, e, which passes up through the opening d, and is secured between the end c and the main portion of the wire, a recess, f, being formed near the end c in the wire, in which the free end of the strip fits, and held securely therein by said end, pressing it against the main portion of the wire.

Instead of the shield C, constructed as shown, a leather mitten or glove may be substituted therefor, with the strip e cut out from it or attached to it in any suitable manner.

By having the implement constructed to pass over all of the fingers and be grasped, as before described, with the husking-point projecting over and beyond the forefinger, the implement can be held firmly and easily in the hand when the fingers are closed, the loop B conforming to the natural position of the hand when the fingers are closed, whereby the implement is adapted to be more handily used and better under the control of the operator, and without any liability of chasing the hand.

Having thus fully described our invention, we do not wish to be understood as claiming, broadly, a corn-husking implement adapted to pass over the fingers with a husking-point projecting over the forefinger, and curved or bent for the reception of the thumb; but

What we do claim is—

The herein-described corn-husking implement, constructed from a single piece of wire or other suitable material, bent to form the loop B, for the reception of all of the fingers of the hand, and a spring-clasp adapted to secure a leather shield, and with an angular portion, a, projecting over and beyond the forefinger thereof, as and for the purpose specified.

In testimony that we jointly claim the foregoing we have hereunto set our hands this 22d day of October, 1880.

PETER KAUFMAN.
BENJAMIN KAUFMAN.
